DESIGN FOR A DRAWER HANDLE OR SIMILAR ARTICLE

Claus E. Lindberg, Corry, Pa., assignor to Corry-
Jamestown Manufacturing Corporation, Corry,
Pa., a corporation of New York

Application August 8, 1945, Serial No. 121,316

Term of patent 7 years

(Cl. D10—8)

To all whom it may concern:

Be it known that I, Claus E. Lindberg, a citizen of the United States, residing at Corry, in the county of Erie and State of Pennsylvania, have invented a new, original, and ornamental Design for a Drawer Handle or Similar Article, of which the following is a specification, reference being had to the accompanying drawing, forming part thereof, and in which

Fig. 1 is a plan view of a drawer handle or similar article showing my new design;

Fig. 2 is a side elevational view;

Fig. 3 is an end view taken substantially as indicated by the line 3—3 of Fig. 2;

Fig. 4 is a fragmentary bottom plan view taken substantially as indicated at 4—4 of Fig. 2; and

Fig. 5 is an enlarged sectional view taken substantially on the line 5—5 of Fig. 2.

I claim:

The ornamental design for a drawer handle or similar article, substantially as shown.

CLAUSS E. LINDBERG.
